BOBBIN DRAG DEVICE FOR WRAPPING
MACHINES AND THE LIKE

Armand Bès, Paris, France, assignor to William
Oliver Larmuth, Alpraham, near Tarporley,
Cheshire, England

Application May 21, 1932, Serial No. 612,805
In France July 31, 1931

3 Claims. (Cl. 117—41)

In numerous looms using various materials wound up on bobbins or rollers, the braking of these bobbins or rollers must be subject to contradictory conditions if a gentle and uniform unwinding is to be ensured at all times, that is to say, at the starting up, in normal running and on stopping.

The object of the present invention is to obtain an easy and variable braking action over a wide range and which can be actuated either by hand or automatically through a regulating device even during the rotation of the bobbin.

In the arrangement described an example only has been given of a roller with roll of paper wound on it, disposed on the platform of a wrapping machine, but the invention is applicable to all material disposed in a different manner notably on bobbins or rollers.

In the single figure of the drawing given by way of illustration and which diagrammatically shows the new arrangement, a spindle of any kind 1 carries a loose pulley 2 and a fixed pulley 3 and on the other hand a bevel wheel 4 driving another bevel wheel 5 the stub shaft 5' of which

25 rotates in a bore formed in the main support 6. On the end of the spindle 5' of the pinion wheel 5 which is preferably of non-magnetic metal such as bronze, is screwed a member 7 of magnetic metal, carrying two brass nipples 8. On the member 7, is fitted and rendered integral therewith, a plate 9 of non-magnetic metal or of fibre, wood and so on. On this plate is disposed either loose or fixed according to the braking effect desired, a felt 10 on which bears the paper roll 11. On the 30 roll rests a disc of magnetic metal bearing by its own weight on the roll 11 and which, having two holes corresponding to the nipples 8, cannot move in the horizontal plane except in conjunction with the socket. The paper 13 coming from the roll 11 passes over the hook 14 and accomplishes its 35 braiding work around a core passing in a bore formed through all the centre parts. The height of the part 7 is calculated in such a manner that, given the thickness of the paper and of the felt 10, the plate 12 rests on the paper and not the member 7 from which it is separated by a small space.

Around the core 7 and separated from it by a suitable air-gap, is disposed an electro-magnet 15 secured on the support 6. This electro-magnet is energized by a current coming from a source of supply 25 and which circulates through the wires 27 and a movable contact 23 and through a rheostat 28. The wire leading the current to the 50 contact 23 is likewise in communication with the

rheostat 28 through an adjustable contact 22, its two studs 20, 21, the metal spring 19, the metal part 26 and the movable contact 24.

The driving shaft 16 carrying the belt shipper 17 receives at its extremity an insulating wiper 18 integral with the shaft 16 and bearing on the other hand on the spring 19 which is arranged at a slight angle in relation to the shaft 16 as shown in the drawing.

If the assemblage is not in action, the shaft 16, 10 the forks 17 and the wiper 18 occupy the position indicated on the drawing. The belt is on the fixed pulley 3, the bevel pinion wheels 4 and 5 mesh together and set in rotation the iron member 7 as well as the plate 9 and the disc 12 which 15 are integral with one another. The paper 13 which winds onto a core 29 and which is drawn along step by step in a well known manner, therefore passes from the roller 11 disposed in a suitable plane for unwinding, and which is slightly 20 compressed onto the felt 10 by the weight of the disc 12. This pressure already exerts a certain braking action. But in addition, the electric current circulating through the electro-magnet 15 energizes the core 7 which creating an attraction 25 of the disc 12 increases the pressure and consequently the braking action. By displacing the movable contact 23 downwardly and by opening up the rheostat, there is first brought about a diminution and then an interruption of the electric 30 circuit and consequently no braking action; by moving it upwardly, the resistance interpolated is decreased and in consequence causes a more energetic braking action.

When the machine stops the shaft 16 is displaced and causes the belt to move onto the loose pulley 2; simultaneously the wiper 18 causes the spring 19 to descend and brings the contact between the studs 20, 21. The current instead of passing through the rheostat is therefore sent 35 directly to the electro-magnet 15 and can produce an energetic braking action which opposes the inertia of the roller and the sudden unwinding which results. By displacing the movable contact 24 downwardly, this braking action is reduced at the stopping of the machine. In starting up again the shaft 14 is again displaced, the spring 19 lifts and cuts the current in this portion of the circuit and the current takes the value determined by the position of the movable 40 contact 23.

It is therefore possible by displacing the contact arms and by unwinding the roller in a suitable direction to obtain at any moment and even during running, the braking action required and 45 50 55

an automatic variation thereof at the stopping of the loom.

It is also possible to cause the electro-magnet to turn with the core 7 and supply current through appropriate contact brushes.

5 I claim:

1. A bobbin drag device for wrapping machines and the like comprising a bobbin containing material for wrapping, a magnetic member on one 10 side of said bobbin, a non-magnetic member disposed on the other side of said bobbin, means for causing said magnetic member to press upon said bobbin to brake the same, an electro-magnetic field for causing said braking action, the 15 strength of the braking action being altered by varying the strength of the magnetic field.

2. A bobbin drag device for wrapping machines and the like comprising a bobbin containing the wrapping material, a disk of magnetic metal disposed upon said bobbin, a disk of non-magnetic 20

material disposed beneath said bobbin, an electro-magnet, an electric circuit, the electro-magnet being in said circuit, a rotary core member to said electro-magnet, said core member being disposed beneath said non-magnetic disk and a rheostat in said circuit varying the electro-magnetic flux for modifying the braking action.

5 3. A bobbin drag device for wrapping machines and the like comprising a bobbin containing the wrapping material, a disk of magnetic metal disposed above said bobbin, a disk of non-magnetic material disposed beneath said bobbin, an electric circuit, an electro-magnet in said circuit, a rotary core member to said electro-magnet, said core member being disposed beneath said non-magnetic disk, a rheostat in said circuit and 10 means for shunting said rheostat for varying the 15 braking effect.
